CLAIM

The ornamental design for an extruded vinyl rub rail, as shown and described.

DESCRIPTION

FIG. 1 is a top and front perspective view of an extruded vinyl rub rail embodying our new design;

FIG. 2 is a front elevation view thereof;

FIG. 3 is a rear elevation view thereof;

FIG. 4 is a right side elevation view thereof, from which the left side elevation view is a mirror image;

FIG. 5 is a bottom plan view thereof;

FIG. 6 is a top plan view thereof;

FIG. 7 is a top and front perspective view of a second embodiment of the new design;

FIG. 8 is a front elevation view thereof;

FIG. 9 is a rear elevation view thereof;

FIG. 10 is a right side elevation view thereof, from which the left side elevation view is a mirror image;

FIG. 11 is a bottom plan view thereof;

FIG. 12 is a top plan view thereof; view of the design.

FIG. 13 is a top and front perspective view of a third embodiment of the new design;

FIG. 14 is a front elevation view thereof;

FIG. 15 is a rear elevation view thereof;

FIG. 16 is a right side elevation view thereof, from which the left side elevation view is a mirror image;

FIG. 17 is a bottom plan view thereof;

FIG. 18 is a top plan view thereof;

FIG. 19 is a top and front perspective view of a fourth embodiment of the new design;

FIG. 20 is a front elevation view thereof;

FIG. 21 is a rear elevation view thereof;

FIG. 22 is a right side elevation view thereof, from which the left side elevation view is a mirror image;

FIG. 23 is a bottom plan view thereof; and,

FIG. 24 is a top plan view thereof.

The broken lines in the drawings illustrate portions of the extruded vinyl rub rail that form no part of the claimed design.
